UNITED STATES PATENT OFFICE.

ANTON FOSHEIM AND ANDREW SIMONS, OF GRAND HAVEN, MICHIGAN.

REFRIGERATOR.

Application filed February 16, 1922. Serial No. 536,897.

To all whom it may concern:

Be it known that we, ANTON FOSHEIM and ANDREW SIMONS, citizens of the United States, residing at Grand Haven, in the 5 county of Ottawa and State of Michigan, have invented certain new and useful Improvements in Refrigerators, of which the following is a specification.

Our invention relates to improvements in 10 the construction of metal linings for refrigerators, and its objects are: first, to provide a means whereby the metal lining may be subjected to the intense heat necessary for coating one side thereof with porcelain without 15 out the danger of warping or breaking at the corners; second, to provide a means whereby the ice box part of the lining may be securely and easily attached to the front of the wooden enclosing part of the refrigerator, and, third, to provide a means whereby 20 the ice supporting shelf may be placed at any desired distance above the upper wall of the lower section of the refrigerator lining.

25 We attain these objects by the mechanism and construction of parts shown in the accompanying drawing, in which Fig. 1 is a front elevation of the metal lining of the refrigerator with the wooden enclosing 30 frame shown in section. Fig. 2 is a side elevation of the same. Fig. 3 is a plan of the metal lining detached from the frame. Fig. 4 is an elevation of the corner construction as covered by our invention showing one form of connection. Fig. 5 is the 35 same showing another form of connection, and, Fig. 6 shows the same corner as constructed at the present time.

Similar reference characters indicate similar 40 parts throughout the several views.

In the accompanying drawing 1 represents the wooden enclosing frame of a refrigerator. 2, 2', 3, 3', 4' and 5 represent the outlines of the metal lining of the same.

45 In Fig. 1, the dotted outlines 5', 6, indicate the outlines of the front of the wooden enclosing case, 7 and 8 indicating the compartments in the refrigerator for the storage of provisions, &c., and 8' indicates the ice 50 box compartment. The several arrows in Figs. 1 and 2 are represented as indicating the course of air downwardly from the ice chamber through the opening 12 into the lower compartment of the refrigerator, thence around to, and through the opening 55 13 back into the ice chamber, and 14 and 15

are openings for the dripping of water from the ice chamber, all of which is common in all refrigerators of this make. In the common construction of these refrigerators the outturning flanges 2, 3, 3', 4 and 4' are all made of practically the same width, with a very narrow, weak supporting corner on the line $x-x$ of Fig. 6. Our invention consists in making the flange 4 very much 60 wider than any of the others, by means of which several very desirable and advantageous results are attained, as, for instance, with the very narrow, weak connection on the line $x-x$ it is next to impossible to pass 65 the metal through the several heating processes necessary in construction, without having it warp out of shape, or, in many instances, break, and ruin the work already done, which with our construction the width 70 of metal on the line $y-y$ renders it easy and absolutely safe to pass the metal through all of the several heatings necessary in welding, baking the porcelain coating &c.; second, the flange 4 being made 75 as wide as the front cross rail, 5, of the wooden enclosing case enables us to secure the metal lining much more firmly in the case than would be possible with the ordinary construction, and, third, by providing 80 the flange with the slots a , we are enabled to place the brackets 10 at varying heights above the top of the compartment 8, thus enabling us to place the shelf 9, that holds the ice 11, high up, or low down in the ice 85 compartment, as desired.

In the construction of our lining the flanges 4 and 4' may be secured together either by abutting the edges of the flanges together, as upon the line c, d, e and properly welding them, as indicated in Fig. 4, or one may be made to overlap the other, as in Fig. 5, and the two electrically welded together before the coating of porcelain is baked upon the metal.

95 b, b represent screws, or other fastening elements for securing the brackets 10 upon the rails 5 and 5" of the wooden enclosing case 1.

Having thus fully described our invention, 100 what we claim as new in the art, is:

1. In combination with the metal lining of a refrigerator having an L shaped provision compartment, and an ice compartment to one side of the vertical compartment and 105 above the horizontal compartment for the storage of victuals, a broad flange integral 110

with the lining and extending therefrom over the vertical side of the ice box, and a broader flange integral with the bottom lining of the ice box and extending upwardly over the lower end thereof, one end of each flange integrally united with the corresponding end of the other, and the other end of each flange integrally united with an out-turned flange on the remaining front edges 10 of said lining.

2. In combination with the elements covered in claim 1, the broader flange of the ice box provided with vertically disposed slots for facilitating the vertical adjustment of the ice holding shelf. 15

Signed at Grand Haven, Michigan, January 28, 1922.

ANTON FOSHEIM,
ANDREW SIMONS.
